UNITED STATES PATENT OFFICE

105,926

DESIGN FOR A DRESS

David Rosenthal, New York, N. Y.

Application July 21, 1937, Serial No. 70,552

Term of patent 3½ years

To all whom it may concern:

Be it known that I, David Rosenthal, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The star shaped leather elements superimposed upon the front and rear sleeve portions of the dress, in the specific manner as shown, are in conformity with the collar edging and bow trim.

I claim:

The ornamental design for a dress, substantially as shown, and described.

DAVID ROSENTHAL.
